UNITED STATES PATENT OFFICE.

WILLIAM G. HYDER, OF PLAINWELL, MICHIGAN.

MILKING-STOOL.

SPECIFICATION forming part of Letters Patent No. 238,121, dated February 22, 1881.

Application filed December 31, 1880. (No model.)

To all whom it may concern:

Be it known that I, WILLIAM G. HYDER, of Plainwell, Michigan, have invented new and useful Improvements in Milking-Stools, of 5 which the following is a specification.

My invention relates to milking-stools constructed with a support or bench for holding the pail above the ground and a seat for the milkman, all in one device. It has for its object improvements in the construction, whereby the weight of the milkman sitting on the seat causes the device to securely hold the pail in place on its supports, and whereby the device automatically operates to free the pail 15 when the milkman vacates said seat.

The construction of a device embodying my improvements consists in a bench, on the front end of which the pail is located, with an elastic confining bar or rod made of spring metal 20 or its equivalent. On the other end of the bench a stand is located, rigidly secured to said bench. Above the stand is a seat, provided with a pendent pintle, which passes down through a hole in the stand and bench, and 25 loosely located in the same. The pintle has a spiral spring around its lower portion, so arranged that it elevates the seat above the stand when the stool is not in use, and allows it to rest on said stand when occupied by the milkman. A chain or cord connects with the pintle, and with eyes in the ends of the confining-bar around the pail, said cord passing over a leverage-pulley in the front part or leg of the stand.

30 In the accompanying drawings, forming a part of the specification, Figure 1 is a side view of the device and pail complete; Fig. 2, top view; Fig. 3, rear view; and Fig. 4, perspective view of front end, showing construction 35 of front leg.

A is the bench, on an incline forward, supported by double leg y and legs F F. This construction of legs provides the stool with the advantageous effect of four legs, to prevent 40 it from upsetting, and yet approximating the results effected in a three-legged stool when located on uneven ground. The legs F F extend up through the bench A and help sup-

port the stand C. Post E is set at an oblique angle with legs F F and post L, in order to 50 brace the stand. D is the seat; v, the pintle, with spring s, having shoulder i resting on its upper end, the lower end of said spring resting on the bench A. The stand C and seat D incline slightly to the rearward, though said 55 incline has no particular bearing on the successful operation of my device. c is the cord or chain, secured to the pintle N by a staple, or by tying it around said pintle under shoulder i. e is the pulley in post L. r r are the 60 elastic metal bars, secured to and supporting the confining-bar a around pail B. Eyes or rings c' c' are formed in the ends of rod a, through which chain c is located, as shown in Fig. 2. In this figure a top view of a lower 65 socket of pail B is shown—on dotted line in Fig. 1.

In the operation of the device, as the milkman sits on seat D, he places the pail in place on bench A, when, by his weight, the seat and 70 pintle is forced down till said seat rests on stand C. This draws on cord c, which causes confining-rod a to rigidly engage the pail. When the milkman rises from the seat, spring s raises it up again, which slackens cord c, and as bars 75 r r and rod a are made of elastic material, the rigid engagement of the rod a is removed from the pail, thus automatically freeing it.

What I claim is—

1. In a milking-stool constructed with bench 80 A and stand C, the seat D, with shouldered pintle v and spring s, in combination with elastic bars r r and elastic rod a, and cord or chain c, passing over pulley e in post L, and connecting with said pintle and confining-rod, all substantially as set forth and shown.

2. The bench and stand and seat, with pendent pintle and spring, the elastic confining-rod, and elastic bars, said rod connecting with the pintle by means of a cord or chain passing 90 through the post, all in combination, substantially as set forth, for the object specified.

WILLIAM G. HYDER.
